(57) **CLAIM**

The ornamental design for a lipstick tube packaging container as shown and described.

DESCRIPTION

FIG. 1.1 is a perspective view of the lipstick tube packaging container showing my new design;

FIG. 1.2 is a right side view thereof;

FIG. 1.3 is a left side view thereof;

FIG. 1.4 is a rear view thereof;

FIG. 1.5 is a front view thereof;

FIG. 1.6 is a top plan view thereof; and

FIG. 1.7 is a bottom plan view thereof.

The broken lines shown in the drawings illustrate portions of the lipstick tube packaging container that form no part of the claimed design.

1 Claim, 7 Drawing Sheets
